UNITED STATES PATENT OFFICE.

LOUIS C. TIFFANY, OF NEW YORK, N. Y., ASSIGNOR TO THE TIFFANY GLASS AND DECORATING COMPANY, OF SAME PLACE.

DESIGN FOR A LAMP.

SPECIFICATION forming part of Design No. 30,665, dated May 2, 1899.

Application filed February 1, 1899. Serial No. 704,185. Term of patent 7 years.

To all whom it may concern:

Be it known that I, LOUIS C. TIFFANY, of the city of New York, borough of Manhattan, in the county and State of New York, have 5 invented and produced a new and original Design for a Lamp, of which the following is a full, clear, and exact description.

Reference is to be had to the accompanying drawings, forming a part of this specification, 10 in which—

Figure 1 is a perspective view of a lamp embodying my design, and Fig. 2 is a front view of the lamp.

As shown in Fig. 1, the hollow shell-like 15 body of the lamp has spiral convolutions, and

one end of said body is open, while a transverse aperture appears at the center of the convolutions. Within the shell-like body appears a lamp or bulb arranged so as to face the opening of said body.

The leading feature of the design consists in the design forming the subject-matter of the accompanying illustration.

I claim—

The design for a lamp, herein shown and 25 described.

LOUIS C. TIFFANY.
